Primary Examiner—Louis S. Zarfas*Assistant Examiner*—Robert A. Delehanty(74) *Attorney, Agent, or Firm*—Quarles & Brady LLP(57) **CLAIM**

The ornamental design for a lavatory, as shown and described.

DESCRIPTION

In a preferred embodiment, the nature of this product is as a plumbing fixture primarily useful for washing the face and hands of humans.

FIG. 1 is a top plan view of a lavatory embodying my new design;

FIG. 2 is a front elevational view thereof shown on a reduced scale, the rear elevational view being identical to the front elevational view shown;

FIG. 3 is a right side elevational view thereof, the left side elevational view being identical to the right side shown; and, FIG. 4 is a bottom plan view thereof.
